CLAIM

The ornamental design for a display screen panel with clock dynamic graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a first image of a front elevation view of a display screen panel with clock dynamic graphical user interface, showing my new design;

FIG. 2 is a second image thereof;

FIG. 3 is a third image thereof; and,

FIG. 4 is a fourth image thereof.

The long dash-short dash line indicates the boundary of the display screen. The short dash-short dash lines and broken text represent unclaimed text areas, text, or graphical features that form no part of the claimed design. The appearance of the animated images sequentially transitions between the images shown in FIGS. 1-4. The process or period in which one image transitions to another forms no part of the claimed design.
